UNITED STATES PATENT OFFICE.

GEORGE A. SCHWEBEL AND JOHN F. SCHWEBEL, OF LANCASTER, PENNSYLVANIA.

SWITCH-OPERATING DEVICE.

No. 927,684.

Specification of Letters Patent.

Patented July 13, 1909.

Application filed November 10, 1908. Serial No. 461,966.

To all whom it may concern:

Be it known that we, GEORGE A. SCHWEBEL and JOHN F. SCHWEBEL, citizens of the United States, residing at Lancaster, in the county of Lancaster and State of Pennsylvania, have invented certain new and useful Improvements in Switch-Operating Devices, of which the following is a specification, reference being had therein to the accompanying drawing.

Our invention relates to switch-operating devices of that class which are used to shift the switch-tongue on street railways, and of that particular class which are operated from the car.

The objects of our invention are to produce a simple, positive and durable device of this class and also one that may be operated from the platform of the car by the motorman without interfering with his regular duties. While still another object of our invention is to provide a device of this kind secured to the car-truck in such a way that lateral movements of the car body will in no way affect the operation or relation of the device with relation to the road bed or track.

With these and other objects in view, our invention consists in certain novel construction and combination of parts as will hereinafter be fully described and claimed, reference being had to the accompanying drawing forming part of this application and in which like figures of reference refer to corresponding parts in all the views. But it is fully understood that while we have herewith described our invention as herewith illustrated, slight changes may be made in the construction and arrangement of the parts without departing from the spirit of the invention.

In the drawings:—Figure 1, is a sectional elevation of a partial view of a car showing our device attached thereto and in a position for operating a switch. Fig. 2, is a front view of our device in detail as attached to the car-truck frame. Fig. 3, is a partial plan view of a rail and switch-tongue showing the operation of our device. Fig. 4, is an enlarged top plan view of one of our switch throwing shoes. Fig. 5, is a side elevation of the same.

Referring to the drawings, 1, indicates the usual end brace of the car-truck, to which is secured the plate 2, which is formed with the outwardly projecting arm 3, provided with the horizontal bearing 4. Mounted within said bearing 4, and the bearing brackets 5,

which are also secured to the end brace 1, are the rocker-shafts 6, which are provided with the collar 7, designed to bear against said bearings 4, and 5, and restrict the thrust of said rocker-shafts 6. Said rocker-shafts 6, are provided with the levers 8, which are pivoted thereto in such a manner as to compensate for any lateral movement of the car body, such as that produced in the act of rounding a curve. While upon the outer ends of said rocker-shafts 6, are rigidly secured the heads 9, at or near a central point thereof. Said heads 9, being formed with the transverse orifices 10, near the ends thereof. Hingeably secured by their upper ends within said orifices 10, are the lifting-rods 11, to the lower ends of which are adjustably and detachably secured the shoes 12, while the action of said lifting-rods 11, are guided by the bearings 13, which are formed in the frame 14, which is secured to the truck end 1.

The shoes 12, are in the general form of a crescent with the two engaging points 15, and are detachably secured upon the lifting-rods 11, by being slipped over the end thereof and secured by the screw 16, which is threaded into the end of said rod 11, while the upward movement of the shoe is restrained by the tension spring 17, which is passed through and around said rod 11, thus forming a collar, while its ends 18, are bent downward and engage orifices in the upper surface of said shoe 12, for the purpose of keeping one of the engaging edges 15, of the shoe in contact with the rail so that it will readily engage the switch-tongue when released from the guard rod 19, by the lowering action of the lifting-rod. It may here be stated that by the use of a shoe of this form, when one of the engaging edges 15, becomes worn the shoe may be reversed to bring the other end into use.

The guard rods 19, are for the purpose of keeping the shoes from contact with the rail when not in use and are secured to the frame 14, and engage the side of the shoe when same is in a normal position, and also serve to restrain the turning action of the tension spring, and it will here be noted that as the shoe is lowered it will extend below the top of the rail before it is released by said rod, so that it cannot swing too far around to prevent its catching the rail.

The operation of the device is controlled by the connecting-rods 20, which are attached

at their rear ends to the levers 8, and at their forward ends to the hand-levers 21, which are mounted upon the car-platform in the usual way and secured in a normal position by 5 the rod 22, and catch 23, which engage the notched quadrant 24.

The operation of our device is so simple and will be so readily understood from the foregoing description that it will not be necessary to go into the matter more fully.

Our invention having thus been described, what we claim as new and desire to secure by Letters Patent is:—

1. In a switch-operating device of the 15 class described, comprising a frame secured to the car-truck and formed with vertical bearings near the ends thereof, lifting-rods mounted in said bearings, shoes formed with reversible switch-tongue engaging ends and 20 detachably secured upon said lifting-rods, tension springs secured upon said rods in contact with the upper surface of said shoes and having their ends detachably secured to said shoes, means for raising and lowering said 25 lifting-rods and means for operating said raising and lowering mechanism from the car.

2. In a switch-operating device of the class described, comprising a frame formed

with extending arms containing vertical 30 bearings and secured to the car-truck, lifting-rods mounted in said bearings, engaging shoes detachably and adjustably secured upon said lifting-rods, guard rods secured to said frame and adapted to co-act with said 35 shoes and limit the swivel action thereof, supporting bearings secured to said car-truck in a higher plane than said frame, rocker-arms journaled in said bearings, cross-heads secured upon the outer ends of said rocker-arms and provided with orifices to receive 40 and retain the ends of said lifting levers, said rocker-arms formed with transverse orifices, swivel levers having their lower ends rotatably secured in said orifices, connecting-rods 45 secured to the upper ends of said levers and a hand-lever mounted upon the car-platform with its lower end secured to said connecting-rod and adapted to operate the same and the mechanism thereto attached.

In testimony whereof we affix our signatures in presence of two witnesses.

GEORGE A. SCHWEBEL.
JOHN F. SCHWEBEL.
